Primary Examiner — T Chase Nelson*Assistant Examiner* — Kelly L Gross(74) *Attorney, Agent, or Firm* — Sughrue Mion, PLLC(57) **CLAIM**

The ornamental design for an ultraviolet ray irradiator as shown and described.

DESCRIPTION

FIG. 1 is a perspective view of an ultraviolet ray irradiator, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view showing a state in which an ultraviolet ray irradiating part is rotated; and,

FIG. 9 is a reference view showing a state of being attached to a ceiling surface.

The broken lines show portions of the ultraviolet ray irradiator that form no part of the claimed design. The dot-dash broken lines indicate the boundary of the claimed design, and form no part thereof. The broken lines in FIG. 9 show environment and also form no part of the claimed design.
